FRANCIS T. FRACKER, OF BOSTON, MASSACHUSETTS, ASSIGNOR
TO P. AND F. CORBIN, OF NEW BRITAIN, CONNECTICUT.

Design No. 3,353, dated January 26, 1869.

DESIGN FOR A HINGE.

The Schedule referred to in these Letters Patent and making part of the same.

To all whom it may concern:

Be it known that I, FRANCIS T. FRACKER, of Boston, in the county of Suffolk, and State of Massachusetts, have invented or produced a new and original Design for Hinges; and I do hereby declare the following to be a full, clear, and exact description of the said invention, reference being had to the annexed drawing, making part of this specification, wherein—

Figure 1 is an elevation of one leaf of a hinge, showing the design upon the face thereof, and

Figure 2 is a similar view, showing the design upon the back of the hinge.

My invention does not relate to the shape of the hinge, and it is not confined to any particular size of hinge, or to any character of joint for uniting the parts or leaves forming the hinge.

My invention or production consists in the design of an ornamentation upon the surface of the hinge.

The interior face or faces of the hinge are formed with a recessed or countersunk ground-work, *aa*, having a surface in imitation of lace, or roughened.

The ornamental scroll-work *bb* is united by an ornament at *c*.

The character and shape of the ornamental scroll-work are shown in the drawing, fig. 1.

The ground-work *dd* of the ornamentation upon the back part of the hinge is to be the same as the ground-work *aa*, and the ornamental scroll-work *ee* is of the character represented in the drawing, fig. 2.

What I claim, and desire to secure by Letters Patent, is—

The design of the ornamentation for the surface of hinges formed of the scroll-work, substantially as shown in the drawing.

In witness whereof, I have hereunto set my signature, this 29th day of December, A. D. 1868.

FRANCIS T. FRACKER.

Witnesses:

C. P. COX,
J. E. HOBBS.
